GAUGE GLASS FITTING

Filed Dec. 1, 1927

Inventors:

Inventor:
George Ernst
orney Geo. A. Beeler

By his attorney Geo. H. Beeler

UNITED STATES PATENT OFFICE

GEORGE ERNST, OF NEWARK, NEW JERSEY

GAUGE-GLASS FITTING

Application filed December 1, 1927. Serial No. 236,971.

This invention relates to combined valve body and gauge head structure.

One object of this invention is to provide a structure of the type set forth in which the 5 gauge head is detachable from the valve body and includes improved means for rendering the head fluid tight.

A further object of this invention is the provision of a device of the nature described 10 in which improved means is provided for adjustably limiting the movement of the valve stem.

Another object of the invention is the production of a device of the character specified, 15 in which improved means is provided permitting the valve to be ground in without disassembling the various parts associated therewith.

A still further object of the invention is to 20 furnish a structure of the species mentioned having improved means for making the stem fluid tight in the valve body.

Still another object of the invention is the production of a device as above set forth having 25 an improved stem guiding and coacting frame on the valve body.

Still a further object of the invention is to produce a device as herein described, wherein 30 an improved removable valve seat structure of a renewable type is provided.

A still further object of the invention is to create a device of the character described having 35 a stem guiding and coacting frame secured in an improved way to the valve body.

With the foregoing and other objects in view the invention consists in the arrangement and combination of parts hereinafter described and claimed, and while the invention is not restricted to the exact details of 40 construction disclosed or suggested herein, still for the purpose of illustrating a practical embodiment thereof reference is had to the accompanying drawings in which like reference characters designate the same parts in the several views, and in which—

Figure 1 is a side elevation of a valve body and a lower gauge head, embodying the invention.

Fig. 2 is a plan view of the device shown in 45 Fig. 1.

Fig. 3 is a vertical section taken on the line 3—3 of Fig. 2.

Fig. 4 is a vertical transverse section taken on the line 4—4 of Fig. 2.

Fig. 5 is a sectional detail view taken on the 55 line 5—5 of Fig. 2.

Referring in detail to the drawings, 10 denotes a device embodying the invention, one opening of which is through the co-acting gauge head, as will be set forth hereinafter. 60 Said device includes a valve body 11. Mounted in the said body is a rotatable stem 12, operative by a lever 13, to the arms of which are connected hand chains 14. This permits the valve to be controlled as desired, irrespective 65 of its elevation.

Connected to the valve body 11 is a gauge head 15, in which is secured a gauge glass 16 for indicating the fluid level in a boiler, or the like. Said head has removable connection 70 with the body, which connection permits said head to be rotatably adjusted about its axis, transversely to that of the body 11. The connection mentioned takes preferably the form of a conventional union coupling 17 which is 75 internally threaded to engage a nipple 18 extending laterally from the valve body.

The construction of the gauge head is of the type described in my co-pending application, Serial No. 185,142, filed April 20th, 1927. 80 Briefly set forth, however, the same comprises a split gland 19 for the gauge glass packing, (not shown). The portions of said gland are caused to operatively bear on the packing by means of a yoke structure 20 mounted on 85 the head 15, and having a pressure exerting screw 21 coacting therewith. More specifically, the yoke 20 includes a cross member 20^a which is threaded to receive said screw, and to which are pivotally connected at 20^b 90 the arms 20^c on the ends whereof the gland portions are mounted, as by threading at 20^d. The end of screw 21 may have fixed but rotatable bearing connection with the head 15 as shown at 21^a so as to be retained thereon. 95 Since the screw is on a side of the head opposite to the gland, it is apparent that on tightening the screw, the said gland will compress the packing to make the glass 16 fluid tight.

In order to effect a tight connection be- 100

tween the head 15 and the body 11, a gland 22 may act on a gasket 23 set into a recess in the said body, as a result of tightening the coupling 17, after the head has been adjusted 5 at the desired angle with respect to the body.

Mounted on the valve body is a frame 24 which is rotatable about the axis of the stem 12, and includes a cylindrical member 24^a, adapted to receive an annular extension 11^a of the body. Extending from said member 24^a are a pair of side arms 24^b which are joined together in a cross member 24^c. The latter is provided with an outward extending boss 24^d which is threaded internally to engage a screw portion 12^a of the stem 12, whereby the latter is operative for opening or closing the valve. Said boss is also externally threaded to engage a stop or cap 25. The said cap is adjustably screwed onto said 15 boss to cause the end wall 25^a thereof to abut the adjacent end of the screw portion 12^a so as to limit the rotation of the stem for opening the valve. A set screw 26' serves to fix the said cap in adjusted position.

25 The said frame may be secured to the body 11 by a plurality of screws 26 which are transverse to the axes of the frame and body, being threaded through the ring 24^a to abut the annular extension 11^a on which the said 30 ring is rotatably received. A groove 11^c may be formed in said extension into which the pressure ends of said screws may enter, regardless of the angularity of the frame 24. Thus the last mentioned part will be held 35 against unintended rotation or movement away from the valve body. The screws 26 form a simplified and improved connecting means, which, on being loosened, permit the said frame to be rotated in its position on the 40 valve body for grinding in the valve, as will be described hereinafter.

To make the stem 12 tight in the said body, a plurality of packing members 28 are disposed therein between the stem and the inner 45 side of the annular extension 11^a. A gland 29 is adapted to compress the packing members, the latter being forced inward of the valve body by bolts 30 that are pivotally secured at 31 to the ring 24^a of the said frame. 50 These bolts are swingable laterally into the slots 29^a formed in flanges 29^b projecting from said gland 29, so that on tightening down the wing nuts 32, the gland is operatively actuated. Since the plane of the bolts 30 is trans- 55 verse to that of the arms 24^b, said wing nuts are easily accessible.

A valve seat structure includes a tubular member 34 removable from the valve body and considerably elongated to permit a plurality of new seats to be cut thereon as desired in the event that a seat 34^a thereof becomes worn or injured. Said member 34 is preferably coaxial with the valve 35 borne by the stem 12. The aforementioned member 60 may be externally threaded to be screwed

into a sleeve 11^d of the valve body. A gasket 37 may be set into a recess in the end of said sleeve for coaction with a shoulder 34^b of the member 34. The latter member may also have a head 34^b to facilitate gripping 70 thereof by a tool so as to permit removal of the member from the valve body externally. At the outer end of said member 34, the same may be provided with a nipple 34^c for connection to a threaded device, as, for example, a flanged fitting 40. A co-operating gasket 41 may render the connection mentioned fluid tight.

The valve 35 may be of any standard construction. As shown, it includes a stud 42, which enters a central bore in the adjacent end of the stem 12, to which end the stud is secured by a pin 43.

To permit the valve body to be drained when necessary, a tap cock 44 is connected thereto in downward extending position. A packing member 45 insures tightness of the joint.

In operation, should it become necessary to grind in the valve 35, the screws 26 may be eased up in the groove 11^c to permit the frame 24 to be rotated in its position on the valve body. The stem 12 can be turned to bring the said valve into snug seating relation, and the cap 25 may be moved into abutting or stop engagement with said stem. Accordingly, on rotating the said frame to and fro, in the usual manner, the valve will be ground in.

I claim:

1. A device of the character set forth in- 100 cluding a valve body, and a gauge head having lateral detachable connection therewith, said body carrying a coaxial yoke structure, a packing gland, and adjustable means to cause the yoke structure to exert pressure on said gland.

2. A device of the character described in- 110 cluding a valve body, a movable stem there- in, a frame on said body, said stem being threaded in said frame, packing in the body for the stem and an adjustable cap on said frame independent of said packing and co-acting with the stem to limit the movement of same.

3. A device of the character described in- 115 cluding a valve body, a movable stem there- in, a frame on said body, means for making the stem tight in said body, a gland bearing on said means, and a bolt coacting with the frame and the gland for exerting pressure on the latter, said frame having a ring co- axially surrounding and engaging the valve body detachably to secure the frame thereto and permit rotation of the frame at a con- 120 stant plane with respect to the valve body.

4. A device of the character described in- 130 cluding a valve body, a rotatable stem there- in, and a frame mounted exteriorly on said body movable into a fixed portion of adjust-

ment, said stem being threaded in said frame, about the axis of said stem, and means on said frame adapted to limit the rotation of said stem.

5. A device of the character described including a valve body, a rotatable stem therein, packing in the body for said stem, and adjustable means on said body independent of said packing for limiting the rotation of said stem, a gland for said packing, and means to bear on the gland, the adjustable means bearing on the first mentioned means.

6. A device of the character described including a valve body, a rotatable stem therein, a frame on said body rotatable about the axis of said stem, said stem being threaded in said frame, and an adjustable threaded member coaxially carried by said frame externally of the valve body and adapted in conjunction with said frame to coact with the stem for limiting the rotation thereof and of the valve relative to said frame.

7. A device as set forth in claim 4 wherein said frame includes a ring surrounding the body, and screws extending through the ring to said frame secure the frame to the valve body, the latter having an annular groove to receive the screws.

8. A device of the character described including a valve body, a stem therein, said body and said stem having respectively a coacting seat and valve, and means having threaded engagement with said stem, said means being rotatable at a fixed distance from said seat to turn the stem to cause the valve to be ground in coincident with said rotation, said body and said means having one of them a pin and the other a circular groove coaxial with the valve and lying in a plane at right angles to the axis of the valve, said pin engaging in said groove to retain said means rotatably in engagement with the body.

9. A device of the character described, including a valve body, a stem therein, said body and said stem having respectively a coacting seat and valve, means having threaded engagement with said stem, and a stop to prevent rotation of the stem relative to said means, said means being rotatable at a fixed distance from said seat to cause the valve to be ground in on rotating said means, said body and said means having one of them a pin and the other a circular groove coaxial with the valve and lying in a plane at right angles to the axis of the valve, said pin engaging in said groove to retain said means rotatably in engagement with the body.

10. A device of the character described including a valve body, a stem therein, and a frame on said body rotatable about the axis of said stem into a fixed position of adjustment, the latter being threaded in said frame, the body having a groove, the frame having

pin means engaging in said groove to be retained thereby in engagement on the body during rotation.

In testimony whereof I affix my signature.

GEORGE ERNST.
